ROBERT V. MORSE, OF ITHACA, NEW YORK.

COOLING SYSTEM FOR HOMOPOLAR MACHINES.

1,327,350.

Specification of Letters Patent.

Patented Jan. 6, 1920.

Application filed September 13, 1917. Serial No. 191,268.

To all whom it may concern:

Be it known that I, ROBERT V. MORSE, a citizen of the United States, residing at Ithaca, in the county of Tompkins and State of New York, have invented a new and useful Cooling System for Homopolar Machines, of which the following, taken with the accompanying drawings, is a specification.

0 This invention relates to dynamo-electric machines of the homopolar type,—particularly to the current collecting elements thereof,—and has for its objects the ventilation and cooling of the armature and brushes, 15 reduction of the size of the armature and current collecting apparatus, and the reduction of brush wear by the use of thorough cooling and moderate brush pressures; and other objects as will appear.

20 In the drawings, Figure I is a longitudinal view partly in section, on the line I—I of Fig. II,—showing the ventilating system applied to a bipolar-homopolar machine.

Fig. II is a transverse cross-section on the 25 plane II—II of Fig. I,—showing the arrangement of brushes and cooling system.

Fig. III is a transverse cross-section on plane III—III of Fig. I, but on a slightly smaller scale,—showing the manner in which 30 the air blast is introduced by way of the field structure.

Fig. IV illustrates another manner of introducing the air blast.

Fig. V is a longitudinal view, partly in 35 section,—similar to Fig. I,—but showing the cooling system applied to a unipolar machine,—that is, a machine having but one homopolar field.

Fig. VI shows more in detail and on a 40 larger scale the brushes and cooling apparatus.

Fig. VII is one view of a brush.

Fig. VIII shows one of the elements from 45 which a laminated brush may be built up.

Fig. IX shows another of the brush elements, which together with those of Fig. VII go to make up a brush.

As shown in Fig. I and Fig. II of the drawings, the armature 1 is mounted on the 50 shaft 2 and carries on or near its cylindrical surface armature conductor bars 3, which extend in a general axial direction. These conductors 3 are shown in Fig. I arranged in two belts or zones 3' and 3'',—each zone enclosing the armature in the region of a 55 homopolar field, as will be described later.

On each border of each armature bar zone is a belt of collector segments 4, 4', 4'', 4''',—similar in appearance to commutator segments, though the operation of the machine 60 does not involve commutation. Each armature bar 3 connects at each end with a collector segment 4, whereby the current is conducted to and from the armature bar. The armature bars 3 are insulated from each 65 other and from the armature core,—as are also the collector segments 4.

Surrounding the armature 1 and extending substantially the full length thereof, is the field structure 6, composed of a number 70 of axially extending ridges which unite near the armature 1 to form annular polefaces 8, encircling the armature. This field structure 6 having the polefaces 8 is excited by the coils 9 to produce a magnetic flux as indicated by the dotted circles of arrows in the upper part of Fig. I. The two end magnetic circuits combine with the central magnetic circuit, so that one broad homopolar field is formed in the region of the zone 3' of the 80 armature, and another broad homopolar field of opposite polarity passes through the zone 3'' of the armature. The narrow homopolar fields at the ends of the armature are shown as left bare of armature conductors, though 85 of course they may be utilized in cases where the added power justifies the extra brush space. The fields above described are homopolar because the magnetic circuit is similar in each ridge of the field structure 6, so that 90 an armature conductor 3 cuts a field of the same polarity at all points in its rotation; for example, the magnetic flux may be considered inward at all points in zone 3' and outward at all points in zone 3''. 95

The brushes 10, 10', 10'', 10''', are arranged in sets or belts corresponding to the collector segments 4, 4', 4'', 4''', as shown in Fig. I, and each set of brushes encircles the armature as shown in Fig. II. Since 100 there is no commutation of the armature current, the individual brushes of a set are placed close together as shown in Fig. II and Fig. VI, so as to form a practically continuous belt around the armature. The 105 narrow spaces between the successive brushes of a set are sufficient to prevent a short-circuit through a collector segment 4. The brush sets lie in annular recesses or channels in the field structure, encircling 110 the armature. The ridges of the field structure 6 bridge over these channels as shown

at 11 in Fig. I and Fig. II, and the brushes 10, 10', etc. are accessible at points where the hollows between the ridges of the field structure open into the brush channels. Stationary conductors 12 connect the brushes from one side of an armature zone to the other,—the connections generally being arranged so as to put groups of armature bars 3 successively in series as they pass under the brushes in rotation, thus building up the voltage of the machine to the desired extent. The operation of the electric circuit of the machine is described more in detail in the Patent No. 1,271,061, for dynamo-electric machine, granted to me July 2, 1918.

In homopolar machines it is highly desirable to keep the diameter of the armature as small as is possible with the required power output; for though there is no electrical limitation to the R. P. M., the peripheral velocity has mechanical and practical limitations. While a high R. P. M. is desirable, particularly in turbine driven generators, it is also desirable to keep the peripheral velocity down, and therefore from both considerations it is highly important to have the diameter of the armature as small as is feasible for a given power output. On the other hand, the power output at a given speed depends largely on the amount of magnetic flux available in the homopolar fields; and since all the effective flux must pass through the core of the armature 1 where saturation limits in practice the flux density in the iron, it is essential that every available square inch of the cross-section of the armature core be utilized for the magnetic flux—that is, that the core be solid iron without the usual ventilating passages. It avails but little to widen the pole faces and lengthen the armature conductors in an effort to increase the voltage; the result is merely to weaken the field. If the flux in the armature core remains the same, the voltage will be the same, since the number of lines of flux cut by the armature conductor is unchanged so long as the amount of flux through the armature core is unchanged. A little calculation will show that the width of an annular pole face need only equal one fourth the diameter of the armature core in order to have the same area and flux density; or where magnetic circuits are combined, the width of the annular pole face need only be equal to one half the armature diameter. Hence it is the flux density in the core, rather than at the pole face, which is the controlling factor.

Thus it will be seen that it is highly important to get as much magnetic flux as possible through the armature core. For this reason the core should be solid, without the usual air passages which offer a very poor path for the flux. In prior machines

constructed with the ordinary ventilating passages through the armature core, the result has been to so increase the diameter of the armature that, with an R. P. M. little better than in commutating machines, the peripheral velocity was high and the machines unduly bulky for their power output.

It is also important to cool the armature conductors 3 and the brushes 10,—particularly the latter,—in order to permit good current densities and thus keep down the size of the current collecting apparatus,—as well as to prevent excessive wear at the brushes and collector segments. The ventilating system about to be described does not choke the flux in the armature core, and directs a blast of air over the armature conductors 3 and collector segments 4 and around and through the brushes 10,—the brushes having thin copper leaves which draw off and radiate the heat from the contact surfaces.

This ventilating system consists of a fan or blower 14 preferably attached to the armature 1, though a separate blower might be used. Leading from this blower is an air duct 15 which conducts the air to a slot 16, which extends through the annular pole face of an active armature zone 3' or 3". Referring now to Fig. VI, it will be seen that the slot 16 passes through the pole face at a point between the brushes 10, where the armature conductors 3 leave a brush for an instant as they pass on to the next brush. The ventilating slot 16 thus does not interfere with the effective field, nor unbalance the currents in the armature conductors that are carrying the load. Not only does the slot 16 not interfere with the operation of the machine, but it positively aids the operation by having the trailing leaf of the brush lie in a line with the slot 16 where the field is weakened, thus choking the current in each armature conductor 3 as it is leaving the brush and preventing sparking at the brush tip. Sparking may be similarly reduced at brushes where there is no ventilating slot 16 by cutting a slot 17 across the pole face as shown in Fig. VI,—so as to weaken the field at the trailing end of the brush.

Each brush 10 is composed of a number of thin copper leaves 18, extending from a solid back 19, (preferably laminated), which back has a flange 20 along one side in order that the brush may be clamped against the end of a stationary conductor 12 leading the current to or from the brush. The leaves 18 are separated from each other where they join the back 19, and may be slightly separated all the way out to their tips. One method of constructing such a brush is shown in Fig. VII, Fig. VIII, and Fig. IX. Referring to Fig. VIII,—21 shows a copper stamping,

made from thin copper of the thickness of a brush leaf, and having the general shape of the back, flange and leaf. In Fig. IX the numeral 22 indicates another copper stamping of the general shape of the back and flange but without the brush leaf. The stamping 22 may be made from metal rolled so as to be a little thicker at the upper edge and tapering to slightly thinner metal at the lower edge,—so that the stampings 22 when assembled will make the brush curve to conform to the curve of the armature. The brush 10 may then be built up of a number of the stampings 21 and 22 arranged alternately, as shown in Fig. VI, the stampings 22 acting as spacers for the brush leaf stampings 21. The stampings 21 and 22 are bolted or welded together, and thus give a brush with a solid laminated copper back 20 19 and a flange 20, having a large number of copper leaves 18 spaced slightly apart from each other. In a similar manner, each individual brush leaf might be made of a number of thinner stampings without spacers 25 between them, and the spacers might then be wider and arranged at intervals, as for example after every fourth or fifth leaf stamping.

The adjustment of the brushes described 30 involves a peculiar property of this arrangement of brush leaves. As the brush is pressed down by the hand, each leaf will at first bend freely as an independent unit, and since the leaves are thin and flexible, the resistance to pressure is comparatively slight. As soon however as the tips of the leaves come into contact with each other as they 35 bend, a new set of forces comes into play; each leaf, which formerly bent as a beam held 40 at one end only, now bends somewhat in the manner of a beam held at both ends. The resistance to pressure becomes suddenly much greater, as can be readily felt by the operator. By simply noting with the hand 45 this marked change in pressure as the brush is pressed in, the operator can know when the tips of the brush leaves come in contact with each other, and lock the brush in place accordingly. The brush pressure per square 50 inch is light, since the total area of the brush is large; and the pressure is automatically maintained without further attention for a considerable length of time, since each brush leaf acts as a spring and straightens up as it 55 wears, thus maintaining the contact. Each small leaf may yield to inequalities of the contact surface without disturbing the brush contact as a whole. It will also be noted that at the contact surface the brush tips 60 merge to form a collecting face substantially equal in area to the back of the brush, while in the part of the brush where the current is flowing through the brush leaves the conductors are thin, with a large radiating 65 area exposed to a blast of air.

The relation of these brushes to the ventilating system will now be apparent. The brushes are close together and encircle the armature at each side of an armature zone. The air forced through the ventilating ducts 70 15 and slots 16 is thus confined in a thin annular chamber surrounding the armature conductor zone and corresponding to the air gap of the machine. The thickness of this chamber or air gap is exaggerated in the 75 drawing for the sake of clearness. The air can only escape by passing through the brushes in the spaces between the leaves, or through the narrow spaces between the brushes. The armature conductors, the 80 brushes, and their trailing tips, are thus thoroughly cooled. The collector segments are also cooled by the air blast,—particularly as most of their heat is radiated 85 through the brush leaves.

One or more blowers 14 or air ducts 16 may be used for each armature zone, or a single source may supply a number of zones; and the air duct may either be placed in the hollows between the ridges, as shown in 90 Figs. II and III, or may pass through other parts of the field structure as shown in Fig. IV. The brushes and ventilating system have been described, for purposes of illustration, in connection with a bipolar homopolar machine,—but are equally applicable to any number of homopolar fields. Thus for example Fig. V illustrates the system applied to a machine using only one homopolar field. Other variations in the details 100 of the brushes and ventilating system will be apparent to those skilled in the art.

Having described my invention, and shown one form of the embodiment thereof, I claim:

1. In a homopolar dynamo-electric machine, the combination of a homopolar field structure having an annular pole face, an armature having a zone of armature conductors adjacent the pole face but spaced therefrom to form an air gap therebetween, brushes closely spaced circumferentially around the armature and bordering and substantially inclosing the air gap, an air duct passing through the pole face in the region 110 of the trailing tip of a brush so as to weaken the field where an armature conductor has its connection with a brush interrupted, and means for forcing a current of air through the air duct into the air gap, and from the 115 air gap out between the brushes.

2. In a homopolar dynamo-electric machine, the combination of a homopolar field structure having an annular pole face, an armature having a zone of armature conductors adjacent the pole face but spaced therefrom to form an air gap therebetween, brushes closely spaced circumferentially around the armature and arranged in belts 125 bordering and substantially inclosing the air 130

gap, an air duct communicating with the air gap by way of the field structure and opening into the air gap between the bordering belts of brushes, and means for forcing a current of air through the air duct into the air gap, and thence through the bordering brushes.

3. In a ventilating system for homopolar dynamo-electric machines, the combination of a field structure producing a homopolar field, a zone of armature conductors lying in said field and surrounded by an air gap, collector segments electrically connected with the armature conductors, brushes closely spaced circumferentially and arranged in belts bordering and substantially inclosing the air gap, the brushes being composed of a large number of flexible leaves secured together and spaced at their outer end but free to bend at their inner end where they contact with the collector segments, the space between leaves diminishing as they approach their inner contact ends so that the contact face of a brush is substantially continuous, and means for blowing air from the air gap through the leaves of the brushes.

4. In a ventilating system for homopolar dynamo-electric machines, the combination of a field structure producing a homopolar field, a zone of armature conductors lying in said field and surrounded by an air gap, collector segments electrically connected with the armature conductors, brushes closely spaced circumferentially and arranged in belts bordering and substantially inclosing

the air gap, the brushes having curved laminated backs and being composed of a large number of flexible leaves secured together and spaced at their outer end but free to bend at their inner end where they contact with the collector segments, the space between leaves diminishing as they approach their inner contact ends so that the contact face of a brush is substantially continuous, and means for blowing air from the air gap through the leaves of the brushes.

5. In a homopolar dynamo-electric machine, the combination of a homopolar field structure having an annular pole face, an armature having a zone of armature conductors adjacent the pole face but spaced therefrom to form an air gap therebetween, brushes closely spaced circumferentially around the armature and bordering and substantially inclosing the air gap, an air duct passing through the pole face in the region of the trailing tip of a brush so as to weaken the field where an armature conductor has its connection with a brush interrupted, means for producing a similar effect at the trailing tip of another brush, and means for forcing a current of air through the air duct into the air gap, and from the air gap out through the brushes.

In witness whereof I have hereunto set my hand this 7th day of September, 1917.

ROBERT V. MORSE
